UNITED STATES PATENT OFFICE.

CLARENCE ELWOOD PRYOR, OF BINGHAMTON, NEW YORK

PNEUMATIC PIANO-PLAYER.

No. 892,887.

Specification of Letters Patent.

Patented July 7, 1908.

Application filed November 15, 1907. Serial No. 402,284.

To all whom it may concern:

Be it known that I, CLARENCE E. PRYOR, a citizen of the United States, and a resident of Binghamton, in the county of Broome and State of New York, have invented an Improved Pneumatic Piano-Player, of which the following is a specification.

My invention is an improved supplemental adjustable abstract attached to the lifting rod interposed between the piano playing keys and the wippen or rocking lever forming part of the hammer-actuating mechanism.

The construction and arrangement of parts embodying my invention are as hereinafter described and shown in accompanying drawings, in which

Figure 1 is a vertical section of a piano player action provided with my improvement. Fig. 2 is a partly sectional side view showing my invention applied to the abstract. Fig. 3 is a face view of the parts shown in Fig. 2. Fig. 4 is a vertical section of a pneumatic player action showing the local relation of my improved abstract regulating attachment to the pneumatics.

In Figs. 1 and 4, A indicates one of the keys of a piano, A' a pneumatic lever, and B a string on which the hammer C is arranged to strike. These parts and the hammer-operating mechanism including the wippen D and vertical rod E' interposed between the said wippen and lever A, are constructed and arranged in a well known manner. The rod or so-called abstract E', is also connected with the frame of the action of the piano by means of a pivoted link F and rests on a screw G attached to the piano key A, as usual in this class of instruments. Hitherto,

the pneumatics in this class of piano actions have been so arranged relatively to the abstracts or lifting rods that operatively connect the keys and hammer mechanism, that access to the abstracts could not be had without first removing the pneumatics. In other words, in the usual arrangement, the three rows of pneumatics commonly employed extend the whole length of the piano, and when once in place, nothing behind them can be reached for adjustment, repair, or other purpose; hence, it is necessary to remove the pneumatics bodily, which is very objectionable for obvious reasons. More frequent adjustment of the player action is required than of the manual action, because it is used and wears more, and it is also subject

to expansion and contraction. I have devised and successfully employed an attachment of the abstract which is easily accessible and may be quickly adjusted as occasion requires, and without removing, displacing, or disturbing the pneumatics proper. To this end, I provide a bar E—see Fig. 2, 3 and 4—which is secured adjustably to the front side of each abstract, or lifting rod, E', and extends nearly the whole length of the same, or as near to the wippen D and screw G as practicable. It is provided with two lengthwise slots e² and e³, and held on the abstract by two screws e³ and e^{3'}, which pass through the respective lower and upper slots as shown. The lower screw e³ is merely a guide on which the bar E slides when adjusted up or down, and the upper screw e^{3'}, is used as a clamp for holding the part E at any point to which it may be adjusted. Hence, the bar E is loose and slidable on the lower or guide screw e³ and is clamped tightly by the upper screw e^{3'}.

It will be seen that the prolongation of the attachment E and the location of the upper or clamping screw e^{3'} with reference to the pneumatics H are such that said screw is accessible above and over the pneumatics, so that a long screw-driver or other suitable tool x may be used for adjusting the screw as indicated by dotted lines Fig. 4. Hence the required adjustment of the bar E may be easily and quickly effected without shifting or removing the pneumatics, thus effecting an important economy in time, labor and expense. It is also obvious that said adjustment can be made by any person without previous experience.

What I claim is—

1. In a pneumatic piano player action, the combination with finger keys, a lever A', pneumatics proper arranged above the finger keys, and hammer-actuating mechanism including an abstract or lifting-rod located behind the pneumatics, of a supplemental adjustable abstract attached to said abstract and consisting of a vertically slideable bar extending nearly the entire length of the abstract and above the pneumatics, and having two lengthwise slots, spaced apart, a guide projecting into the lower slot, and a clamp-screw passing through the upper slot, and located above the pneumatics, whereby it is accessible for manipulation in the manner shown and described.

2. The improved pneumatic piano player

action, comprising pneumatics proper, finger keys, a lever connected with the pneumatics, a hammer-operating mechanism including an abstract or lifting-rod supported on the finger keys, and a supplemental adjustable abstract attached to said abstract, whose lower end is in contact with the said lever, and provided with a guide, and its upper end extend-

ed on the abstract and having a clamping device which is accessible over and above the pneumatics as shown and described.

CLARENCE ELWOOD PRYOR.
